UNITED STATES PATENT OFFICE.

WILLIAM LEWIS EVANS, OF WASHINGTON, INDIANA.

RING-JOINT MACHINE.

Application filed November 10, 1926. Serial No. 147,529.

This invention relates to a ring joint machine, adapted to be used in joining trim, molding, or other material, by what is known as a ring joint. In making this type of joint, after the pieces to be joined are cut in the proper shape, channels or grooves are cut in their rear faces, in such a manner as to form a continuous circular channel when the pieces are properly joined. While the pieces 5 are clamped in this position, a ring is forced into this channel, and this ring is of such a size and shape that it will exert a forceful gripping action against the inner wall of the channel and hold the joint tightly together.

The construction of the present invention is similar in some respects to that shown in my earlier application, Serial No. 52,445, filed August 25, 1925, but has been considerably modified with the object of obtaining 15 simplicity of construction and operation, as well as lightness and compactness, and economy in production. The production of joints with the present machine may be a little slower than with the former machine, but 20 this loss of time is almost negligible when compared with the saving in capital investment, and the low cost of upkeep. This advantage is more apparent, when it is noted that the operator of the present machine 25 need not be a skilled machinist.

The specific construction of the present invention, together with its objects and advantages, will be more fully explained in connection with the accompanying drawings, 30 which illustrate the same in its preferred form.

In the drawings:

Figure 1 is a side elevation of the machine.

Figure 2 is a front elevation thereof.

Figure 3 is a rear elevation thereof.

Figure 4 is a vertical longitudinal section taken substantially centrally of the machine.

Figure 5 is a plan view of the work table and the cutter, the adjacent part of the frame being shown in section.

Figure 6 is a detail view of the bracket for positioning the work, and the means for adjusting the same.

Figure 7 is a detail sectional view showing the ram, and the means for supporting and actuating the same.

Figure 8 is a section taken on the line 8—8 of Figure 7.

Figure 9 is a detail sectional view through 55 the fan and its housing.

The machine, which constitutes the subject

matter of the present invention, comprises a U-shaped main frame 1 supported by legs 2, which are secured thereto by cap screws or bolts 3, formed at their upper ends with 60 upstanding projections 4, adapted to hold various cutters, sleeves and other attachments when they are not in use. The legs 2 are rigidly held in laterally spaced relation by 65 transverse tie rods 5.

The frame casting 1 is formed at its front end with an upstanding cylindrical housing 6, at the upper end of which a work table 7 is secured. Mounted for sliding longitudinal adjustment on this table is a gage bracket 8, 70 the shape of which will depend upon the character of the joint to be formed. In the present instance, I have shown a bracket used for making corner joints, and having a right-angled seat 9, against which rest the ends 75 of the two pieces to be joined. The bracket 8 is formed with a rearwardly projecting socket 10, in which a guide rod 11 is secured.

A ram 12 is used for clamping the work to the table 7 while the circular channel is 80 being cut, as well as for forcing the ring into the channel for completing the joint. This ram 12 is supported in an overhanging head 13, which constitutes an integral part of the frame 1. The ram is removably secured to 85 a stem 14, which is guided for vertical movement in a guideway 15 formed in the head 13. A number of interchangeable rams may be provided of different sizes. The stem 14 is formed on one side with rack teeth 16, 90 which engage with the teeth of a pinion 17, adapted to be rotated to raise or lower the ram.

In the present construction, in order to 95 simplify the mechanism, the pinion 17 is driven from a horizontal shaft 18, mounted in the head 13 in rear of the stem 14, and adapted to be rotated by means of a hand wheel 19 secured to one end thereof. Any approved form of speed reduction gearing 100 may be used to connect the shaft 18 to the pinion 17. In the construction shown, the head 13 is extended at one side to form a gear housing 20, which is provided with a removable cover plate 21. The shaft 18 extends into this housing, and the pinion 17 is formed with a hub 22, which also extends into the housing, and a gear 23 keyed to the hub 22 is driven by a pinion 24, keyed to the extended portion of the shaft 18.

When the two pieces to be joined have been 110 placed upon the table 7, against the seat 9,

the ram 12 is lowered to clamp the work to the table, and a circular channel is cut in the bottom face of the work thus held by means of a cutter 25, secured to the upper end of a vertical shaft 26. This shaft is slidably, as well as rotatably, mounted in a bearing 27 in the front part of the frame 1, and the shaft, while rotating, may be raised to bring the cutter 25 into contact with the wood. The bearing 27 is lubricated by means of a grease cup 28.

The shaft 26, extending downwardly below the frame 1, has a pulley 29 secured thereto, which is connected by a belt 30 to a pulley 31, driven by an electric motor 32. This motor is secured by studs 33 to a plate 34, constituting part of the rear portion of the frame 1. This plate 34 is provided with various holes 35, properly spaced to meet the requirements of different types of motors, which may be used for driving the cutter.

The vertical movement of the shaft 26 is controlled by means of a pedal 36, which may be conveniently fulcrumed intermediate its ends on the front tie rod 5. The pedal 36 is pivotally connected at its rear end, as at 37, to the lower end of a link 38, which is connected at its upper end, as at 39, to a thrust collar 40, mounted on the shaft 26 beneath the pulley 29, and held on the shaft by a retaining collar 41. The pedal 36, in front of its fulcrum, carries a pin 42, to which is connected a stop rod 43. This stop rod projects upwardly through a flange at the front edge of the frame 1, and is provided at its upper end with an adjustable nut 44, thereby limiting the downward movement of the pedal, and consequently limiting the upward movement of the cutter shaft 26, and regulating the depth of the channel to be cut. As soon as the pedal 36 is released, the cutter and pedal are restored to their initial position by a contractile coil spring 45, which connects the upper part of the link 38 to the pedal at a point in front of its fulcrum. The action of the coil spring draws the pedal 36 upwardly, and at the same time draws the thrust collar 40 and the cutter 25 downwardly. The limit of this retractive movement is determined by an adjustable screw 46, mounted in the lower port of the link 38 and engageable with a shoulder 47, formed on the rear part of the pedal 36.

In order to remove the chips and shavings as fast as they are cut, a fan 48 is secured to the shaft 26 immediately beneath the cutter 25, and the housing 6 which surrounds the cutter. The fan is formed with an outlet 49 through which the shavings are blown.

In order that the machine may be used for making joints of different sizes, corresponding to different widths of molding, a number of cutters 25 of different sizes may be interchangeably used, and the table 7 is likewise formed with a number of openings 50, corre-

sponding to the different sized cutters. The table is, therefore, mounted for circumferential adjustment about a central pin 51, secured in the frame adjacent the housing 6, and the various positions of the table about the central pin 51 may be determined by a spring-held pin 52 mounted in the front part of the housing 6, and engageable with any one of a plurality of recesses 53, formed in the down-turned edge of the table. The table 7 has one side without a hole 50, which is brought beneath the ram when the rings are to be forced into place.

In order that the stock may be placed in proper position for cutting the channel and for applying the ring thereto, the gage bracket 18 is guided and adjusted by means of the rod 11, which is mounted in side flanges 54, formed on the rear part of the frame. This rod is provided with two collars 55, which can be adjusted longitudinally of the rod and secured by means of set screws 56. A keyway 57 is provided on the rod for receiving the points of the set screws, so as not to scar the rod when changing their positions. A flat spring 58 is secured to the frame behind the rod 11 to hold the collars in position. In joining casings of considerable width, it is desirable to use two rings. In such case, the collars 55 may be set so that one collar engages the spring to hold the bracket 8 in position for cutting one channel, and the gage may then be shoved back, causing the collar to override the spring, and allowing the other collar to engage the spring to hold the bracket in position for cutting the second channel. In other words, the collars 55 and spring 58 provide an adjustment which will hold the stock in either of two positions, depending on whether the gage bracket is pulled out or pushed in.

In the operation of the machine, after selecting a cutter 25 and a ram 12 of the proper size for the stock which is to be worked upon, the table 7 is adjusted so that the hole 50, which is over the cutter, will be of a size corresponding to the size of the cutter. The gage bracket 8 is then adjusted to proper position. The two pieces to be joined are placed upon the table, and the ram 12 is lowered to clamp them in position. The pedal 36 is then depressed to raise the cutter 25 into contact with the wood. The nut 44 on the stop rod is adjusted so that when the pedal is depressed as far as possible, the channel will be cut to the proper depth. After the channel has been cut, the work is turned over, and a ring is forced into the channel by means of the ram 12, which is made cup-shaped for this purpose. By using a suitable type of speed reduction gearing in the housing 20, a tremendous force may be applied to the ram by means of the hand wheel 19. For further details in regard to the method of applying the ring to the channel,

and in regard to the various type of rings which may be used, reference may be had to my co-pending application above mentioned.

5 It will be noted that a machine constructed according to the present invention has comparatively few parts which can get out of order. The operation of the machine is very simple, so that even a novice will find 10 no difficulty in using it. The cost of manufacture is also comparatively small, yet it is capable of producing joints which are identical in every respect with those which can be produced by more expensive machines.

15 While I have shown and described specifically one form in which the invention may be embodied, it is to be understood that various modifications may be made in the structural details thereof without any material departure 20 from the salient features of the invention as expressed in the claims.

What is claimed is:

1. In a woodworking machine the combination of a frame; a table supported on the 25 frame; means for holding the work on the table; a rotatable cutter beneath the table; means for projecting the cutter into engagement with the underside of the work; said table having a plurality of holes of different 30 sizes corresponding to the cutters which may be used, the table being movable to align any one of the holes with the cutter.

2. In a woodworking machine, the combination of a frame; a table mounted on the 35 frame; a rotatable cutter beneath the table; said table having a plurality of holes of different sizes corresponding to the sizes of the cutter which may be used; the table being movable to align any one of the holes with 40 the cutter; adjustable guide means to position the work on the table above the aligned hole; clamp means to hold the work so positioned; and means to project the cutter through the aligned holes and into engagement 45 with the underside of the work.

3. In a ring joint machine, the combination of a frame having a lower arm with a table supported thereon, an upper arm rigidly connected to the lower arm and terminating 50 in a head which overhangs the table, a ram supported by said head, means for moving said ram into engagement with stock supported on the table, a cutter rotatable about a vertical axis beneath the table, said table being 55 rotatably adjustable about its center and having various holes of different size corresponding to various cutters which may be used, means for latching the table with any one of the holes above the cutter, and means 60 for projecting the cutter through the selected hole into engagement with the stock supported by the table.

4. In a ring joint machine, the combination of a frame, a table supported by the frame, a 65 ram mounted above the table and adjustable

into engagement with stock supported thereby, a ring channel cutter supported beneath the table, said table having a plurality of holes of different size corresponding to various cutters which may be used, means for 70 adjustably latching the table so that any one of the holes is above the cutter, and means for projecting the cutter through the selected hole into engagement with the stock supported by the table.

5. In a ring joint machine, the combination of a frame having a lower arm with a table supported thereon, an upper arm rigidly connected to the lower arm and terminating in a head which overhangs the table, a 80 ram supported by said head, means for moving said ram into engagement with stock supported on the table, a ring channel cutter rotatable about a vertical axis beneath the table, said table being rotatably adjustable about its center and having various holes of different size which may be brought into position above the cutter and which correspond to cutters of different size which may be used, said table having one side which is 85 imperforate and adapted to be positioned beneath the ram when the latter is used to apply the ring to the joint, and means for projecting the cutter into engagement with the stock supported by the table when the latter is 90 properly positioned to receive the same.

6. In a ring joint machine, the combination of a frame, a table supported by the frame, a ram mounted above the table and adjustable into engagement with stock supported 100 thereby, a ring channel cutter supported beneath the table, said table being rotatably adjustable about its center and having various holes of different size which may be brought into position above the cutter and which correspond to cutters of different size which may be used, said table having one side which is imperforate and adapted to be positioned beneath the ram when the latter is used to apply the ring to the joint, means 105 for projecting the cutter into engagement with the stock supported by the table when the latter is properly positioned to receive the same, and means for adjustably latching the table in any one of the various positions 110 in which it is to be used.

7. In a ring joint machine, the combination of a frame, a work table supported thereby, a ram supported above the table and movable into engagement with stock supported 120 thereon, a gage bracket resting on the table, a guide rod secured to and extending rearwardly from said bracket, said frame having flanges with holes in which said rod is slideable longitudinally, a spring on the frame 125 between said flanges, and a pair of stop collars adjustably secured on the rod between the flanges and cooperable with the flanges and spring to gage the bracket in either one of two predetermined positions.

8. In a ring joint machine, the combination of a frame, a work table supported thereby, a ram supported above the table, manually operable means to move said ram into engagement with stock supported by the table, a rotatable vertical shaft mounted in the frame beneath the table, a cutter secured to the upper end of the shaft, power-operated means for constantly rotating said shaft and cutter, means for raising said shaft, while it is rotating, to cause the cutter to act on the stock supported by the table, a gage bracket resting on the table, a guide rod secured to and extending rearwardly from said bracket, said frame having flanges with holes in which said rod is slidable longitudinally, a spring mounted on the frame between said flanges, and a pair of stop collars adjustably secured on the rod between the flanges and cooperable with the flanges and spring to gage the bracket in either one of two predetermined positions.

9. In a ring joint machine, the combination of a frame, a work table supported thereby, a ram supported above the table, manually operable means to move said ram into engagement with stock supported by the table, a rotatable vertical shaft supported beneath the table, a cutter secured to the upper end of the shaft, means secured to the shaft below the table for driving the same, a thrust collar on the shaft below the driving means, a pedal fulcrumed on the frame, a link pivotally connected at one end to the thrust collar and at the other end to the pedal in rear of its fulcrum, so that a depression of the front end of the pedal serves to raise the cutter, while rotating, into contact with the stock

supported by the table, a spring connecting the link to the pedal in front of its fulcrum to restore the cutter shaft and pedal to initial position after the pedal is released, co-engaging stop means on the link and pedal respectively, including a shoulder formed on one of these members and an adjustable screw on the other member to adjustably limit the normal retractive movement of the cutter, and stop means connected with the pedal in front of its fulcrum to limit the upward movement of the cutter shaft.

10. In a ring joint machine, the combination of a frame, a work table supported thereby, means for clamping stock to the table to be worked upon, a rotatable vertical shaft supported beneath the table, a cutter secured to the upper end of the shaft, means secured to the shaft below the table for driving the same, a thrust collar on the shaft below the driving means, a pedal fulcrumed on the frame, a link pivotally connected at one end to the thrust collar and at the other end to the pedal in rear of its fulcrum, so that a depression of the front end of the pedal serves to raise the cutter into contact with the stock supported by the table, a contractile coil spring connecting the link to the pedal in front of its fulcrum to restore the cutter shaft and pedal to initial position after the pedal is released, and co-engaging stop means on the link and pedal respectively to limit the retractive movement.

In testimony, that I claim the foregoing as my own, I have hereto affixed my signature.

WILLIAM LEWIS EVANS.
